UNITED STATES PATENT OFFICE.

WALTER JOHN HUBERT JONES, OF PHILADELPHIA, PENNSYLVANIA,
ASSIGNOR TO MAX ROLLE, OF PHILADELPHIA, PENNSYLVANIA.

ELECTRIC FAN.

SPECIFICATION forming part of Letters Patent No. 696,052, dated March 25, 1902.

Application filed January 15, 1901. Serial No. 43,363. (No model.)

To all whom it may concern:

Be it known that I, WALTER JOHN HUBERT JONES, a subject of the Queen of Great Britain, residing at Philadelphia, county of Philadelphia, and State of Pennsylvania, have invented a new and useful Improvement in Electric Fans, of which the following is a full, clear, and exact description, reference being had to the accompanying drawings, which form a part of this specification.

My invention relates to rotary fans of the character ordinarily operated by an electric motor, and has for its object the provision of means whereby the fan may have imparted to it, in addition to a rotation on its axis, a bodily movement of rotation in a horizontal plane, so as to direct a current of air toward every desired part of the room or apartment which it is desired to ventilate.

It also has for its object the provision of means whereby the fan may be bodily rotated through any desired arc of a circle and automatically reversed at the desired end of its movement in each direction.

It also has for its object, broadly, the provision of means whereby the above-described objects may be attained, but which will at the same time permit the fan to be adjusted at any desired angle to the horizontal.

It also has for its object the arrangement of the motor and the immediate driving means for bodily rotating the fan within separate inclosures.

The invention consists of the hereinafter-described mechanism for obtaining the above-mentioned objects and in the general arrangement of the same.

In the drawings, Figure 1 is a side view, partly in section, of the entire mechanism. Fig. 2 is an end view, partly in section, of the same. Fig. 3 is a plan view of the mechanism for imparting a bodily movement of rotation to the fan. Fig. 4 is an enlarged plan view of the motor with one of the field-magnet coils removed. Fig. 5 is an enlarged detached view of the brushes and brush-holders. Fig. 6 is an enlarged detail view of the levers operated by the stops. Fig. 7 is a diagrammatic view of the motor, resistance-switch, and electric connections.

A is the fan, and a the shaft thereof, which

also carries the armature b^2 of the driving-motor.

b^1 b' are the coils of the field-magnet of the motor, one coil being secured to the lower half c of the casing, while the other coil is secured to the upper half c' of the casing. The upper half of the casing is hinged at c^2 to the lower half.

d d' are the bearings for the shaft, the same consisting of a ball- and -socket joint, the socket being formed by the opposing parts of the halves of the casing.

e e' are the commutator-brushes, inserted loosely in pockets formed partly in the upper half and partly in the lower half of the casing. Each pocket is formed with an inner lining of brass f and an outer wall of insulating material f' , such as fiber.

g g' are springs bearing against the brushes and holding them in contact with the armature.

By swinging up the upper half of the casing on its hinge ready access is afforded to the internal parts of the motor, to the bearings, and to the brushes. The brushes can thus be expeditiously renewed.

H is the base of the machine, and I the immediate support for the motor-casing, the support I being adapted to revolve in a horizontal plane over the base H by means to be hereinafter described. The lower half c of the casing has projecting from its base a lug c^3 , extending between lugs i^1 i^2 , projecting from the top of the support I. Extending through lugs c^3 , i^1 , and i^2 is a bolt i^3 , having a holding-nut i^4 . By means of these devices the motor-casing and fan may be adjusted at any desired angle to the horizontal and held securely in their adjusted positions.

The support I and the upper part of the base H form a casing or inclosure which contains the driving mechanism for imparting the desired movement of bodily rotation or reciprocation of the fan on a vertical axis. The driving mechanism will now be described.

Secured to the support I is the shaft i^5 , which extends down through the inclosure and has its bearing in the base H.

k is a bracket depending from the top of the support I, said bracket having bearings for the shaft of the worm K and bearings for

the shaft of the worm-wheel K'. The worm-wheel K' is in driving engagement with the worm K, which is the immediate driving power for the inclosed driving mechanism 5 and which is driven by the means hereinafter described. Secured to the shaft of the worm-wheel K' is a bevel-wheel K², which may be either a gear-wheel or a friction-wheel.

l is an arm depending from the top of the bracket k.

l' is a shaft turning in bearings in arm l.

L L' are bevel-wheels on the shaft l'. By sliding the shaft either bevel-wheel L or L' may be brought into driving engagement with 15 the bevel-wheel K², thereby rotating shaft l' in one direction or the other.

L² is a spur gear-pinion secured to one end of the shaft l', said pinion engaging a circular rack H', secured to the base H.

20 It will be readily understood that by imparting a movement of rotation to the worm K the shaft l' is driven in one direction or the other, and as the pinion L² on the end thereof is in engagement with the fixed rack H' the shaft l' will have imparted to it a bodily movement of rotation in a horizontal plane about the axis of the circular rack H', thereby imparting a similar movement to the entire inclosed driving mechanism, the support 25 I, the motor-casing, motor, and fan. In other words, the entire machine above the stationary base H will be rotated in a horizontal plane. The support I has an annular rim i⁶, which contacts with annular projections h and h' on the base H.

30 In order to drive the worm K, I provide a flexible shaft M, connecting the armature-shaft and the shaft of the worm, said flexible shaft extending through an orifice in the support I.

35 I provide the following means for automatically reversing the rotation of the fan, motor, and support.

N is a lever secured between its ends to 40 pivot n, rotatably supported by the bracket k. One end of lever N extends outwardly through support I, while the other end is connected to shaft l'.

N² is a leaf-spring secured to the lever N, 45 said spring engaging a pin N³, secured to the bracket k. The spring N² holds the lever N firmly in the illustrated position, thereby holding the bevel-wheels L' and K² in engagement.

50 Secured to the annular rim h are stops O O in line of travel of the lever N. After the machine is started the lever N will in its movement in one direction engage one of the stops O, thereby turning it on pivot n and 55 sliding the bevel-wheels L and L', with their shaft l', disengaging wheel L' from wheel K² and causing the spring N² to slip over the pin N³. As soon as the spring engages the opposite side of the pin it will quickly turn the pivot n still farther and move the wheel L into engagement with wheel K². The machine now rotates in the reverse direction

until lever N engages the other stop O, which again reverses the machine. The stops O are adjustable along the rims h and are held 70 in their adjusted position by means of the holding-screws o.

The resistance-coil P is located within the base H, and under the resistance-coil is a switch Q. The in-feed and out-feed wires 75 R R of the circuit extend from the resistance-coil up through the top of the base and are then connected, respectively, to the annular contact-plates S S.

TT are brushes secured to arm l and contact- 80 ing, respectively, with the contact-plates S S. From the brushes TT the wires R R lead up through the support I and motor-casing to the motor.

For the flexible shaft M may be substituted any other device which will permit the fan to be adjusted without disengaging the driving connection between the armature-shaft and the worm K. Nor do I limit myself to any other of the specific devices hereinbefore described, except wherein such devices are expressly claimed, as it is obvious that various details of structure may be modified without departing from the invention. 95

Having now fully described my invention, what I claim, and desire to protect by Letters Patent, is—

1. The combination, with the fan, of a motor for imparting thereto a movement of rotation about its own axis, driven mechanism for rotating the fan bodily about a vertical axis, adjusting means for setting the fan and motor at different angles to the horizontal and a driving connection, independent of the fan, adapted to be maintained in engagement with the motor and the driven mechanism at different adjusted positions of the fan and motor. 100

2. The combination, with a motor and its shaft, of a fan on said shaft, whereby the fan has imparted to it a movement of rotation about its own axis, driven mechanism for rotating the motor and fan bodily about a vertical axis, adjusting means for setting the fan 105 and motor-shaft at different angles to the horizontal and the driven mechanism, and a flexible shaft connecting the fan and motor-shaft and the driven mechanism. 115

3. The combination, with the fan and the motor for rotating the fan on its own axis, of a worm, a driving connection between the motor and the worm, a worm-wheel driven by the worm, a bevel-wheel on the worm-wheel shaft, a pair of bevel-wheels on a second shaft, 120 means for moving either of the last-mentioned bevel-wheels into engagement with the first-named bevel-wheel, a pinion on the second shaft, a stationary circular rack in engagement with the pinion, and a support upholding 125 the motor, worm, worm-wheel, bevel-wheels and pinion. 130

4. The combination, with the fan and the motor for rotating the fan on its own axis, of

a worm, a driving connection between the motor and the worm, a worm-wheel driven by the worm, a bevel-wheel on the worm-wheel shaft, a pair of bevel-wheels on a second shaft, 5 an operating-lever for moving either of the last-mentioned bevel-wheels into engagement with the first-named bevel-wheel, a pinion on the second shaft, a stationary circular rack in engagement with the pinion, a support up-10 holding the motor, worm, worm-wheel, bevel-wheels, pinion, and operating-lever, and stationary stops in line of travel of the operating-lever.

5. The combination, with the fan, of an elec-15 tric motor for rotating the same about its own axis, a support upholding the motor and fan, a base on which the support is adapted to rotate, driven mechanism for imparting to the support, motor and fan a movement of rota-20 tion about a vertical axis, a driving connection from the motor to the driven mechanism, a resistance-coil, the base and support being

shaped to inclose the driven mechanism and the base being shaped to inclose the resistance-coil.

25

6. The combination, with a motor-casing, of a motor rotatable in said casing, a fan on the motor-shaft, a base having a circular rack, a horizontal shaft above said base, a pinion on said shaft engaging said rack, driven mech-30 anism above said base adapted to rotate said shaft, a support sustaining said motor-casing above it and said driven mechanism, shaft and pinion below it, and a driving connec-35 tion from the motor to the driven mechanism, said support and base inclosing said driven mechanism, shaft, pinion and rack.

In testimony of which invention I have here-unto set my hand, at Philadelphia, Pennsyl-vania, on this 9th day of January, 1901.

WALTER JOHN HUBERT JONES.
